UNITED STATES PATENT OFFICE.

CHARLES JOHNSON, OF MINNEAPOLIS, MINNESOTA.

LUMBER CUT-OFF MACHINE.

1,427,297.

Specification of Letters Patent. Patented Aug. 29, 1922.

Application filed May 14, 1921. Serial No. 469,731.

To all whom it may concern:

Be it known that I, CHARLES JOHNSON, am a citizen of the United States, residing at Minneapolis, in the county of Hennepin 5 and State of Minnesota, have invented certain new and useful Improvements in Lumber Cut-Off Machines; and I do hereby declare the following to be a full, clear, and exact description of the invention, such as 10 will enable others skilled in the art to which it appertains to make and use the same.

My invention relates to what is known as lumber cut-off machines, and which are used in box factories and wood-working mills, 15 generally, for cutting long boards into short sections of certain but different lengths; and the invention is directed to certain improvements in machines of this kind whereby improved actions are obtained, all as will hereinafter more fully appear.

Generally stated, the invention consists of the novel devices and combinations of devices hereinafter described and defined in the claims.

25 A salient feature of the invention is directed to improved means for moving the power-driven circular saw to and from its work with an interrupted movement or hesitation at the retracted position, whereby an ample period of time is afforded for feeding the lumber in front of the saw and into 30 position to be sawed off.

In the accompanying drawings, which illustrate the invention, like characters indicate like parts throughout the several 35 views.

Referring to the drawings:

Fig. 1 is a plan view of the improved machine;

40 Fig. 2 is a perspective showing the several sections of the stop device; removed from the shaft to which they are normally applied;

Fig. 3 is a section taken approximately 45 on the line 3—3 of Fig. 1;

Fig. 4 is a section taken approximately on the line 4—4 of Fig. 3; and

Fig. 5 is a fragmentary view with some parts sectioned on the line 5—5 of Fig. 3, 50 and other parts being shown in full.

As commercially constructed, the mechanism of the machine is mounted in or on a rectangular framework made up of laterally spaced plate-like side members 6, table top 7 and an inclined deck 8. The table top 7 and deck 8 tie the frames members 6 to-

gether at their upper portions and tie-rods 9 connect the lower portions thereof. In this machine, a circle saw is used and this saw is driven indirectly from a motor, preferably an electric motor, 10, the rotor of which is coupled to a transverse driving shaft 11 journaled in suitable bearing sleeves 12 on the frame members 6. The sleeves 12, as shown, are formed independently of the frame members 6, are inserted therethrough and have flanges adapting them to be bolted to said frame members. The inner ends of the sleeves 12 afford bearings for an up-standing bifurcated saw-supporting frame 13 that operates as a rocker arm and the lower ends of the prongs of which are journaled on the inner ends of the sleeves 12. The frame, 13, at its upper end, has laterally spaced bearings in which a saw shaft 14 or spindle 14 is journaled. The projecting end of the shaft 14 works through a segmental slot 15 formed in the adjacent frame member 6, and just outside of said frame member, said spindle is provided with a circle saw 16. Between the shaft bearings, on the frame 13, the saw spindle 14 is provided with a pulley 17 that is aligned with a pulley 18 on the driving shaft. A belt 19 runs over the aligned pulley 17 and 18 and this belt is kept taut by a tightening pulley 20 journaled to arms 21 pivoted to the oscillatory frame 13 by a shaft 21^a. The numeral 22 indicates a main countershaft that is journaled in the frame members 6 90 and is provided with a frame-operating crank preferably afforded by a crank disk 23 secured thereto and provided on its opposite faces with wrist pins 24 and 25 set, the former circumferentially ahead of the latter.

These wrist pins 24 and 25 co-operate, respectively, with notches 26^a and 27^a in arm-like driving dogs 26 and 27, both pivotally connected to the oscillatory frame 13, as shown, by means of pivot studs 28. The driving dog 27 is gravity-held downward, but the dog 26 is yieldingly drawn upward by a coiled spring 29 attached thereto and to a lug 30 on one of the frame members 6. 105

The main countershaft 22 is driven from the main driving shaft 11 by suitable transmission mechanism, which, as shown, comprises as follows:

The numeral 31 indicates a belt that runs 110 over a pulley 32 on the shaft 11 and over a pulley 33 on a shaft 34. The shaft 34 is

journalized in the frame members 6 and carries a spur pinion 35 that meshes with a spur gear 36 carried by a shaft 37 journalized in the frame members 6 and provided with a sprocket wheel 38. A sprocket chain 39 runs over the sprocket wheel 38 and over a sprocket wheel 40 carried by the countershaft 41 journalized in the frame members 6. The shaft 41 carries a spur pinion 42 that meshes with a spur gear 43 normally loose on the main countershaft 22 but adapted to be coupled thereto, at will, for rotation therewith, by a friction clutch 44 indicated in a general way in Fig. 5 and which clutch 15 may be of any well known or suitable construction.

The vibratory saw-carrying frame 13 is under spring strain to remain in its retracted position, from a coiled spring 45 attached thereto and anchored to a lug 46 on one of the frame members 6, (see particularly Fig. 3).

The numeral 47 indicates a so-called scavenging blade that slides on the upper face of the inclined deck 8 and is provided with depending lugs 48 that work through oblique slots 49 in the deck 8. The lugs 48 are connected by L-shaped links 50 to lugs 51 on the upper portion of the vibratory saw frame 13. The pivotal joints between said elements 48, 50 and 51 are loose, so that the links 50 are capable of lateral movements as they move in the oblique slots 49, for a purpose which will 35 presently appear.

As shown, the extreme vibratory movements of the frame 13 are limited by stops 52 and 53 on one of the frame members 6 and these stops are preferably made 40 slightly adjustable by slot and bolt connections 54.

To support the board or lumber before it is sawed or while it is being set in position to be sawed, there is provided a feed table 45 55, preferably a skeleton structure, suitably supported from the floor and suitably connected to the saw framework. The upper surface of this feed table 55 is slightly above the inclined deck 8 so that that portion 50 of the board that is to be sawed off will stand slightly above the deck until it has been sawed off and dropped onto said deck.

For stopping the boards in various different positions for sawing off therefrom 55 of sections of different lengths, I provide a stop device that includes a long rock shaft 56 journalized in suitable bearings 57 on the table 55 and projecting freely above the deck 8. The rock shaft 56 is provided 60 with a latch lever 58 that co-operates with a notched rock sector 59 shown as secured to the inner bearing 57.

That portion of the rock shaft 56 that overhangs the deck 8 is provided with a 65 multiplicity of adjustable stop fingers 60,

61 and 62, there being, as shown, three in number. These stop fingers have split hubs equipped with clamping screws 63 that adapt them to be normally frictionally secured to the shaft 56 in various different 70 positions for rotation therewith but with freedom for rotary and for axial or sliding adjustments thereon. The stop finger 61 has an offset stop lug 61^a adapted to underlap the finger 60, and the stop finger 62 has a stop lug 62^a adapted to underlap the finger 60 and the finger 61. When the three stop fingers 60, 61 and 62 are assembled as closely together as possible, their stop surfaces will be in the same 80 vertical plane, but the stop lug 61^a will be immediately below the stop finger 60 and the stop lug 62^a will be immediately below the stop lug 61^a. In all of the axial adjustments of the several stop fingers, the above 85 noted adjustment in respect to rotation should be maintained and the latch lever 58 will be arranged for co-operation with the latch arch 59 to rotate the shaft 56 and set any one of the three stop fingers in 90 position to intercept the movement of the board y past the saw and toward the left in respect to Fig. 1.

It also follows that said stop fingers, in view of their lapping relation, may be set 95 to vary by the merest fraction the difference in the lengths of board sections that will be stopped or set for sawing when they are brought into position. Of course, the variation in the lengths of the sections that they 100 will stop in sawing position may be increased to any desired extent within the length of the rock shaft 56 toward the left from the saw in respect to Fig. 1.

The operator, by manipulation of the 105 lever 58, which oscillates the shaft 56, can, by very slight oscillatory movements, quickly bring any one of the three stop fingers into stopping position, and this quickness of action is important especially in sawing 110 box lumber or the like where the operator, by quick inspection of the board that he is moving to position, must determine the advisable length to cut to avoid knots and the like.

As stated, the main countershaft 22 can be thrown into action at will by manipulation of the clutch 44. When said shaft is rotated, the saw-carrying frame 13 will be oscillated backward and forward with a properly timed action and with a hesitating movement which leaves the saw in its retracted position for about one-third of each rotation of said shaft 22. The spring 45 assists in holding the saw and its supporting frame in its retracted position and, when in such position, the free end of the upper driving dog 27 will rest upon the shaft 22 as a stop and the free end of the driving dog 26, by the spring 29, will be 125 130

- drawn upward against said shaft. As the wrist pin 25 moves upward, it engages the notch 27^a of the dog 27 and, under continued rotation of the shaft 22, positively 5 moves the saw frame 13 forward and causes the saw to cut off the positioned board. When the saw has reached its extreme forward position, the driving dog 27 engages the shaft 22, is stopped thereby 10 and the wrist pin 25 then moves out of the notch 27^a, but simultaneously therewith, the wrist pin 24, which is on the opposite side of the crank disk 23 from the wrist pin 25, enters the notch 26^a of the driving dog 26 15 and, under its downward and rearward movement, positively forces the saw frame 13 and the saw 16 back to retracted positions, on the completion of which the dog 26 is stopped by the shaft 22 and said wrist 20 pin 24 moves upward out of the notch 26^a. The exact timing of said movements may be varied, but preferably the saw is moved forward or to its work during about one-third of the rotation of the shaft 22, is 25 given its return movement in little less than one-third of the rotation of said shaft and is left in its idle position during a little more than one-third of the rotation of said shaft.
- 30 At the time the saw completes its movement and the sawed-off board section is dropped off on the deck 8, the scavenging blade 47 will be outward of said dropped board section so that under return movement of the saw and its supporting frame, said blade will scrape said board section backward on the deck 8. Moreover, in view of the oblique slots 49, said blade 47 will be moved endwise away from the saw, thereby 35 carrying the board section endwise out of contact with the saw.
- The efficiency of the machine above herein illustrated, described and claimed, has been demonstrated in actual practice.
- 40 45 What I claim is:
1. In a machine of the kind described, the combination with a saw and a vibratory support therefor, of means for vibrating said support and saw comprising reversely acting driving dogs connected to said support, and a crank-equipped shaft alternately operative on said dogs to oscillate said saw support. 50
  2. In a machine of the kind described, the combination with a saw and a vibratory support therefor, of means for vibrating said support and saw comprising reversely acting driving dogs connected to said support, and a crank-equipped shaft alternately operative on said dogs to oscillate said saw support, 55 said crank being out of action on both dogs for a considerable period of time while the saw and support are in retracted positions.
  3. In a machine of the kind described, the combination with a saw and a vibratory support therefor, of means for vibrating said 60
- support and saw comprising reversely acting driving dogs connected to said support, a crank-equipped shaft alternately operative on said dogs to oscillate said saw support, said crank being out of action on both dogs 70 for a considerable period of time while the saw and support are in retracted positions, and a spring tending to hold said saw support in its retracted position.
4. In a machine of the kind described, the combination with a supporting frame, an oscillatory saw support and a power-driven saw carried by said support, of upper and lower driving dogs connected to said support, and a shaft having two crank-acting 75 wrist pins alternately engageable, one with each of said driving dogs, to oscillate said saw support, said shaft operating as stops to disengage said dogs from the cooperating wrist pins. 80
5. In a machine of the kind described, the combination with a supporting frame, an oscillatory saw support and a power-driven saw carried by said support, of upper and lower driving dogs connected to said support, and a shaft having two crank-acting wrist pins alternately engageable, one with each of said driving dogs, to oscillate said saw support, said shaft operating as stops to disengage said dogs from the cooperating 85 wrist pins, one of said dogs being gravity-pressed downward and the other being spring-pressed upward toward said shaft. 90
6. In a machine of the kind described, the combination with a supporting frame, an oscillatory saw support and a power-driven saw carried by said support, of upper and lower driving dogs connected to said support, and a shaft having two crank-acting wrist pins alternately engageable, one with 100 each of said driving dogs, to oscillate said saw support, said shaft operating as stops to disengage said dogs from the cooperating wrist pins, both of said wrist pins being out of action on the co-operating wrist pins during a considerable period of time while the saw and its support are in retracted positions. 105
7. In a machine of the kind described, the combination with a supporting frame, an oscillatory saw support, a power-driven saw carried by said support, of upper and lower driving dogs connected to said support, said dogs being laterally offset and provided with opposing notches inward of their free ends, 110 the upper dog being yieldingly pressed downward and the lower dog being yieldingly pressed upward, a power-driven shaft extended between said dogs, a disk carried by said shaft and provided on its opposite faces with wrist pins set one ahead of the other and co-operating one with each of said dogs to oscillate said saw support. 115
8. In a machine of the kind described, the combination with a supporting frame, an 120
- 125
- 130

oscillatory saw support, a power-driven saw carried by said support, of upper and lower driving dogs connected to said support, said dogs being laterally offset and provided with 5 opposing notches inward of their free ends, the upper dog being yieldingly pressed downward and the lower dog being yieldingly pressed upward, a power-driven shaft extended between said dogs, a disk carried 10 by said shaft and provided on its opposite faces with wrist pins set one ahead of the

other and co-operating one with each of said dogs to oscillate said saw support, said shaft operating as a stop to disengage said dogs from said wrist pins with properly timed 15 actions, and said wrist pins being so set that both thereof will be out of action for a considerable period of time while said saw and its support are in retracted positions.

In testimony whereof I affix my signature. 20

CHARLES JOHNSON.
